UNITED STATES PATENT OFFICE.

THOMAS P. LUCAS, OF GALVESTON, TEXAS, ASSIGNOR OF ONE-HALF TO
JOHN S. BROWN, OF SAME PLACE.

LOCKING-PAWL FOR ANCHOR-CHAINS.

SPECIFICATION forming part of Letters Patent No. 293,657, dated February 19, 1884.

Application filed June 30, 1883. (No model.)

To all whom it may concern:

Be it known that I, THOMAS P. LUCAS, a citizen of the United States, residing at Galveston, Texas, have invented new and useful 5 Improvements in Locking-Pawls for Anchor-Chains, of which the following is a specification.

This invention relates to improvements in that class of devices employed for stopping the chain cables of vessels for which Letters Patent No. 248,331 were issued October 18, 1881; and my present invention has for its object to provide a novel combination of parts whereby the rising and falling and horizontally-moving clamping-block can be rigidly locked in its engagement with the cable to stop the latter; also, to provide novel means for protecting the wood-work of the vessel from wear as the cable is moved. These objects I accomplish by the construction and combination of parts hereinafter described and claimed, and illustrated in the accompanying drawing, in which—

Figure 1 is a longitudinal vertical section, 25 showing a bow-stopper and an aft-stopper embodying my invention. Fig. 2 is a plan view of the aft-stopper. Fig. 3 is an end elevation of the bow-stopper. Fig. 4 is a detail perspective, showing the forked clamping-lever. 30 Fig. 5 is a plan view of the lower surface of the clamping-block.

A in said drawings indicates the clamping-box, consisting of a base, a , and vertical sides a' . The base a is provided with shallow 35 recesses a^2 , having a length about equal to the length of the separate links, and having an alternating arrangement similar to that shown in Fig. 5, and approximating the alternation of the successive links in such manner that 40 as the cable lies upon the base a the opposite bars of the alternate link will lie in the alternate recesses. The clamping-block B has its lower face recessed in a corresponding manner, as shown at b^2 , Fig. 5, so that the side bars 45 of the same link may lie in recesses upon opposite sides of the base a and the clamping-block B, respectively, as indicated in Fig. 3. The edges of the metal lying between said recesses are rounded, so that the cable may pass 50 over them as it runs out. In the vertical sides a' are formed slots or channels a^3 and a^4 , inclined

at an angle to the base, and at or near the central point of each side is cut an inclined way, a^5 , parallel with the slots a^3 , and passing completely through the side. A portion of the 55 metal upon each side is extended upward to form a lug, a^6 , to which is pivoted a locking-pawl, B' , which is adapted to swing by gravity into a vertical position. This pawl, as shown, is composed of two arms, B^2 B^3 , hung at one 60 end on a pintle, B^4 , which is supported by the lugs a^6 , the other ends of the arms being connected by a rod, a^6 , so that a gravitating bail or yoke-shaped pawl is provided, the said pawl being located directly above the clamping-block, so as to rest on the upper surface thereof. 65

B represents the clamping-block, recessed in the manner described, and having upon each side inclined lugs b^1 and b^2 , which move in the channels a^3 and a^4 and retain the block in 70 parallelism with the base a . Upon the lug b^3 , upon each side, is formed an outwardly-projecting stud, b^4 , which moves in the ways a^5 in the sides of the clamping-box, a perforation being formed near the end of each stud to receive a retaining-pin. 75

Projecting outwardly from the sides a' of the box A are short journals a^6 a^6 , which receive and form fulcrum-bearings for a forked lever, C, formed in two parts, c c , which are united 80 above the center of the clamping-box, and there form an upwardly-projecting shank, c' . In each part of the forked lever C is formed a slot, c^2 , which engages with one of the studs b^4 on the clamping-block, the arrangement being such that the said slots are inclined at an angle to the ways a^5 in the sides a' , so that as the lever is turned upon its bearings a^6 it will raise or depress the clamping-block B, bringing it down upon the chain as the said lever is 85 depressed and lifting it as the lever is raised. Moreover, as the block is drawn down the studs b^4 have a certain degree of play in the slots of the lever, whereby they are brought close to the fulcrum-bearings a^6 , thereby giving an increased power to said lever as the clamping-block engages with the cable. The inclination of the channels a^3 and a^4 gives to the clamping-block a downward and at the same time a forward movement, the latter being in 90 the direction in which the chain cable is running, whereby the friction of the latter upon 95

said block tends to assist the action of the lever C in forcing the block into engagement with the chain. As said block descends, the locking-pawl, which rests upon each side of its upper surface, moves with it until it assumes the position shown in Fig. 1 upon the aft-stopper, whereby the clamping-block is securely locked in engagement with the cable. D indicates a detachable handle, of suitable length, having at one end a socket, d, adapted to receive the shank c' of the lever C. A perforation may be formed in each of these parts to receive a retaining-pin, d'.

In vessels of seven hundred tons and under 15 a single stopper to each cable will usually be sufficient; but in vessels of greater tonnage I propose to employ two—viz., a bow-stopper and an aft-stopper, with the cable passing through both. In this arrangement the aft- 20 stopper may be placed so that the cable may pass from it down to the chain-lockers, as shown in Fig. 1. In this stopper the parts are constructed as already described; but the after ends of the sides a' of the clamping-box 25 are curved and brought together, as shown in Fig. 2 at e. The base a also is provided with a downwardly-projecting flange, f, which forms a bearing-surface for the chain as it runs out or as it is brought in. A similar flange, 30 f', is formed upon the part e, and both depend through the opening in the deck by which the chain passes, and serve to protect the wood from wear. A removable cap, E, is fitted upon the part e, and serves to exclude 35 rain or water washing about the deck.

The position of the parts as well as of the links of the cable is shown in Fig. 3.

The extremities of the handles D may be provided with eyes d' to receive a rope, which 40 may be used to lash the lever down in case of accident to the locking-pawl, or which may be run over a snatch-block to impart additional power to the lever.

When the cable is stopped and the clamping-block locked down by the pawl B', the 45 handle D may be removed and laid aside until it is necessary to use it again.

Having thus described my invention, what I claim is—

1. The combination of the clamping-box, 50 the rising and falling clamping-block, and a pawl pivotally connected with the box directly over the block, and having its free end adapted to fall by gravity and rest upon the upper surface of the block to lock the latter 55 in engagement with the cable, substantially as described.

2. The combination of the clamping-box and the rising and falling clamping-block with the pintle supported by the sides of the box above 60 the block, and the yoke-shaped pawl suspended at one end from the pintle, and having its other end adapted to fall by gravity and rest upon the upper surface of the block to lock the latter in engagement with the cable, sub- 65 stantially as described.

3. The combination of the clamping-box having its sides provided with upwardly-projecting lugs, the clamping-block, and a locking-pawl pivotally connected with the said 70 lugs directly over the clamping-block, and adapted to fall by gravity and rest upon the upper surface of the block to lock the latter in engagement with the cable, substantially as described.

4. The clamping-block A, having its side walls, a', brought together at one end and constructed on its under side with the depending flanges f f', in combination with the clamping-block, substantially as described. 75

5. The combination, with the clamping-block having its sides provided with the inclined slots, and the clamping-block having the lugs b', provided with studs b', of the forked lever C, having the shank c', and the detachable handle D, having a socket adapted to said shank, substantially as described. 80

In testimony whereof I have hereunto set my hand in the presence of two subscribing witnesses.

T. P. LUCAS.
